UNITED STATES PATENT OFFICE.

GEORGE D. COLEMAN, OF ATLANTA, GEORGIA.

MOISTENER.

Application filed September 14, 1923. Serial No. 662,778.

To all whom it may concern:

Be it known that I, GEORGE D. COLEMAN, a citizen of the United States, residing at Atlanta, in the county of Fulton and State 5 of Georgia, have invented new and useful Improvements in Moisteners, of which the following is a specification.

This invention provides a moistener designed to be used on the thumb or finger 10 of the user, and is constructed to insure cheapness of manufacture and sale, and to allow of an adjustment to accommodate itself to the thumb or any finger of the user.

15 More specifically stated, the invention embodies a small sponge which is gripped by one end of a holder, the latter being formed from a single length of bendable material and reversely bent at opposite ends 20 to provide a split finger receiving portion, and a sponge receiving clamp, so that the article can be conveniently and quickly applied to the finger for use, and at the same time allow the sponge to be easily and conveniently replaced by a new sponge when 25 the occasion requires.

In the drawing forming part of this application, like numerals of reference indicate similar parts in the several views, and 30 wherein:

Figure 1 is a view showing the manner of applying the article to a finger in a position for moistening envelopes and the like.

Figure 2 is a detail view of the article 35 removed from the finger.

Figure 3 is a detail view of the holder separated from the sponge.

Figure 4 is a view of the blank from which the holder is formed.

40 Figure 5 is a view showing the arrangement of the article on the finger for moistening the thumb and index finger when handling papers in filing and the like.

The invention consists of but two parts, a 45 small sponge 10, and a holder therefor, the latter being formed from a single length of bendable material of any suitable character, the blank of material being indicated at 11 in Figure 4.

This material is reversely bent at opposite 50 ends somewhat similar to the letter S and in order to form a finger receiving portion or ring 12 and a clamp for the sponge. This clamp is indicated at 13, and can be varied in size by bending one end of the blank 10 55 so that an effective purchase may be had on the sponge to hold it in position for use. It will be noted that the finger receiving portion or ring 12 is split so that it can be varied in diameter by simply bending the material from which it is formed thus allowing the moistener to be placed upon the thumb or any particular finger of the user. The article can be worn with the sponge underneath the finger if the moistener is 60 used for handling or filing papers which cannot otherwise be taken convenient hold of or the moistener can be turned on the finger to reverse the position of the sponge when the article is used when moistening 65 envelopes or the like. The different positions in which the moistener can be arranged upon the finger or thumb is clearly illustrated in Figures 1 and 5 of the drawing. It is manifest that the article in its entirety 70 is very simple in its construction and can be manufactured and sold at a very nominal cost.

While it is believed that from the foregoing description, the nature and advantages 80 of the invention will be readily apparent, I desire to have it understood that I do not limit myself to what is herein shown and described and that such changes may be resorted to when desired as fall within the 85 scope of what is claimed.

Having thus described the invention, I claim:

A moistener of the character described comprising a sponge, and a holder therefor, 90 said holder being formed from a single length of bendable material and reversely bent at both ends to define an open finger receiving portion and a clamp for securing the sponge to the holder. 95

In testimony whereof I affix my signature.

GEORGE D. COLEMAN.
